GOLF TEE

Application filed March 15, 1930. Serial No. 436,068.

This invention relates to new and useful improvements of a vestpocket clover leaf golf tee, and the like primarily designed for use as a tee, on the teeing ground, which is the 5 starting place for a hole.

An object of the invention comprehends the provision and arrangements of means to provide a golf tee easily carried in a folder of vestpocket size.

Another object of the invention is to provide golfers with a golfing tee with an adjustable cup formed in the shape of a clover leaf, to form any desired angle for teeing off.

An additional object of the invention consists of the provision of a reinforced pin to drive easily into solid ground, also to hold firm in soft ground.

With the above and other objects in view, the invention further consists of the following novel features and details of construction to be hereafter more fully described, illustrated in the accompanying drawings and pointed out in the appended claim.

In the drawings:

Fig. 1 is an open view of a folder, vestpocket size, with pencil holder and score cards showing arrangement of vestpocket clover leaf golf tee placed into carrier.

Fig. 2 is a top view showing golf tee from one piece metal formed in condition to place in vestpocket carrier.

Fig. 3 is a cross section of improved cup of golf tee taken through on line 7-7 showing form of cup of clover leaf.

Fig. 4 is a cross section of reinforced pin of golf tee taken through on line 8-8.

Fig. 5 is a perspective view of clover leaf golf tee formed in position ready for use in teeing off.

Fig. 6 is a cross section view through ground showing reinforced pin adjusted to depth in ground with golf ball placed on an adjustable clover leaf formed into a cup to hold golf tee, ready for teeing off.

This invention is primarily intended to assure an adjustable vestpocket clover leaf golf tee by means of construction.

The arrangements of construction is designed for carrying, when not in use, for adjustment, when in use.

The clover leaf golf tee is made from metal easily adjusted into position for use; also to bend back into position for carrier or vestpocket holder, without breaking, when not in use, or after use.

Referring to the drawings in detail where-in like characters or reference denote corresponding parts, the reference-character 9 Fig. 1, indicates a folder of vestpocket size made from leather material.

It is obviously apparent from Fig. 1, of the drawings, that the folder 9 is made up by several compartments to hold separate a block of commonly used golf score cards 10, a pencil holder 11, and a golf tee holder 12, made up from paper sheeting closed at lower end 13, and upper ends 14.

The clover leaf golf tee 15, Fig. 6, is made of one piece of metal consisting of pin 16, a stem 17, and a cup 18, Fig. 2 and Fig. 5.

The pin 16, Fig. 2 and Fig. 5, is formed to a curve 19 as shown in Fig. 4, to reinforce pin 16, also to hold pin 16 firm in soft ground, and easy to drive into hard ground.

The stem 17, Fig. 2 and Fig. 5 remains a flat surface to insure an accurate bending of clover leaf golf tee as shown in Fig. 5 and Fig. 6.

The cup 18, Fig. 2 and Fig. 5 is formed to a radius or curve 20 to give a form fitting to a golf ball 21 as shown in Fig. 6.

It is obviously apparent from Fig. 1 of the drawings that clover leaf golf tee can be carried in a vestpocket holder making it an easy arrangement for a golfer to carry any number of golf tees as desired without bulging pockets.

Having so demonstrated and clearly shown in the drawings a clover leaf golf tee, it will be understood that without much effort, by holding said tee within the fingers of both hands, any desired angle for golf tee may be obtained for teeing off on the golf links by bending into position.

The invention is susceptible of various changes in its form, proportion and minor details of construction, and the right is herein reserved to make such changes as properly fall within the scope of the appended claim.

Having thus described by invention, what is claimed is:

An adjustable golf tee comprising a tapered and transversely curved pin for insertion into the ground, a flat stem integral with one end of the pin, a concaved ball receiving element formed integrally with the other end of the stem, said stem bendable at any point between the ball receiving element and the pin
5 to position said element at various angles relative to the pin and permit the distance between the ball receiving element and the pin to be varied, said ball receiving element having a plurality of tapered slots extending
10 inwardly from the edges thereof and one of said slots of a larger size than the remaining slots with the stem positioned therein permitting the formation of the stem with the ball receiving element to be located inwardly of
15 the edges of the latter and permit the ball receiving element to be easily bent into cup shape.
20

In testimony whereof, I affix my signature.

HARRY O. BRINCK.
